FUEL-OIL VAPORIZER

Application filed April 4, 1927. Serial No. 180,758.

This invention relates to a fuel oil vaporizer, and it has to do particularly with fuel oils of a low grade.

Fuel oils of the character referred to have 5 boiling points which range from 150° C. to 320° C., and the invention aims to provide a device capable of vaporizing such fuel oils with high boiling points so that the same can be used in internal combustion engines.

Accordingly, the invention contemplates a 10 vaporizer in which oil is broken up and air is supplied at one or more points, depending somewhat upon the requirements of the particular engine and the particular oil used, and 15 the passing of the oil and air through a more or less tortuous passageway to effect a thorough mixing. Upon mixing of the oil and air, the same is conducted, or passed into a hot chamber where the oil is thoroughly vaporized, and for this purpose the exhaust 20 gases coming from the internal combustion engine may be used to supply the heat. In the passing of the mixed air and oil into the vaporizing chamber, the heavier particles of 25 fuel are separated from the lighter particles of fuel so that these heavier particles of fuel are brought into close proximity to a heated wall, whereby the vaporization of the heavier particles is better obtained.

Additional features of the invention lie in 30 various adjustments that can be had. These adjustments provide for the regulating of the quantity of air which is supplied to the various points, and moreover, the adjustments 35 permit variation in the tortuous path for the air and broken oil. The invention also contemplates the use of a cleaner for the oil before it passes into the vaporizer, and the vaporizer is constructed so that a higher grade of oil, 40 such as gasoline, can be used until such time as the vaporizer is hot enough to operate, whereupon the gasoline may be shut off and a lower grade of oil supplied to the engine. For this purpose the invention contemplates 45 connected valve structures disposed at appro-

priate points for determining, by a single adjustment, the oil which is to be supplied to the engine.

In the accompanying drawings:

Fig. 1 is a vertical sectional view taken 50 through the vaporizer.

Fig. 2 is a vertical sectional view taken through the cleaner for the fuel.

Fig. 3 is a fragmentary side elevational view of the two devices in operating position. 55

Fig. 4 is a sectional detail of part of the vaporizer construction taken on line 4—4 of Fig. 1.

The fuel oil is preferably supplied under 60 pressure from a tank (not shown), by means of an oil pipe 1 (Fig. 2). The oil pipe 1 is connected to a fixture 2 provided with a valve 3 having an operating lever 4. This valve is for controlling the flow of oil, and the lever is to be connected up to other mechanism, later 65 to be described, so as to operate in unison therewith. From the fixture 2, the oil passes through a channel 5 into a cleaner 6 provided with an inner coarse screen 7, and an outer fine screen 8. The oil passes through the 70 screens out into the channel 9 and then leaves the cleaner through the pipe 10.

The pipe 10 leads into the vaporizer. The vaporizer consists of a body 12 which is cored out and which has an opening 13, into which 75 is fitted a screw threaded plug 14. This plug is adjustable by reason of the wrench receiving formation 15, and can be held in adjustment by a lock nut 16.

This plug is provided with a longitudinal 80 bore which is enlarged at the upper end, as shown at 17, and at the lower end as shown at 18. The walls of the plug around the enlargement 18 are provided with openings 19 arranged in varying vertical positions. The 85 plug is provided with interior threads, and a second plug 20 is designed to be received therein. The oil pipe 10 extends through the plug 20 and the plug 14. Plug 20 is provided with nut formation 21 and it can be 90

locked in position relative to the plug 14 by lock nut 22. The tube 10 extends through the body of the vaporizer, and at its end is provided with a nozzle 25. This nozzle fits within 5 in a pointed recess provided by the plug-like member 26. Fitting within the recess 17 of the plug 14 is a tube 27 which surrounds the oil pipe 10 and extends through the body of the vaporizer, terminating as at 28. It 10 will be noted that a space between the pipe 10 and interior walls of the tube 27 is in communication with the air holes 19 for the passage of air therethrough, the quantity of air being regulable by adjustment of plug 15 20, as will be described in the operation of the device. The body of the vaporizer is provided with a plurality of openings 30 in any suitable number, and cooperating with these openings is a plate 31 rotatably mounted and 20 having an adjusting handle 32. The plate 31 has suitable openings 33 for alignment with the openings 30. This construction is for the entrance of air, and, as will readily be seen, provides for an adjustment to regulate 25 the passage of air.

A spray or baffle plate 35 is secured to the upper end of the tube 27, and a second spray or baffle plate 36 is secured to the tube at a point below the first baffle plate. The tube 30 terminates below the baffle 35, and the tube is provided with a plurality of holes 37 below the baffle 36 so that air which comes in through the tube may pass into the vaporizer underneath and around the edges of the baf- 35 fles.

Secured to the tube, as by means of welding or otherwise, are enlargements in the nature of sprays or baffles 40 and 41, the member 40 being secured to the end of the tube and the 40 member 41 below, and each being below one of the baffles. It is convenient to use pins 42 which rise directly from the member 40 and support the baffle 35. The projecting members 40 and 41 cooperate with projecting portions 43 and 44 in the channeled out portion of the vaporizer body, to thus provide a tortuous passageway through which the air and oil pass.

At this point it is thought that a description 50 of the mixing of the air and oil by the structure thus far described, is desirable. The oil comes from a tank through the cleaner and into the vaporizer through the pipe 10. The oil escapes through the nozzle 25 and is 55 broken up in the pointed chamber surrounding the nozzle. The oil, thus broken up, falls from the pointed chamber and mixes with incoming air through the holes 30 which is the primary air supply. All or some of the 60 mixture now falls on the baffle 35, and air which comes in through the tube 27 and out the end of the tube under the baffle 35 is added to the mixture. The mixture then falls through the passageway 50, and some of the 65 mixture will fall on the baffle 36. At this

point, air coming through the holes 37 is added to the mixture. Air coming through the tube may be termed the secondary supply. From here the mixture travels through the passageway 52 into a center chamber 53 70 where the air and oil are thoroughly mixed. It will be noted that the incoming air through the holes 30 is adjustable by regulating the plate by means of its handle, and also that the air coming through the tube 27 is variable. This is done by positioning the nut or plug 20 properly within the recess 18, thus opening or closing some of the openings 19; or raised and lowered a little bit to varying 75 the size of the openings 19.

Another feature is the fact that the passageways 50 and 52 can be regulated as to size. This is made possible by moving the plug 14 up and down on its threads, which is permissible by loosening the lock nut 16. Inasmuch as the tube 27 fits within the recess in the plug 14 the raising and lowering of the plug raises and lowers the tube, and the enlargements 40 and 41, relative to the stationary enlargements 43 and 44 on the vaporizer body vary- 80 90 ing the size of the passageways 50 and 52. These several adjustments, consisting of the air control and the passage regulation, are made to suit the particular fuel or engine, or both, and after the proper adjustment is attained it will be maintained over a considerable period of time.

The body of the vaporizer is hollowed out to provide passageways 60, 60a, 61, and 61a 100 for hot exhaust gases. The exhaust gases, either all or in part, enter from the rear side of the vaporizer through a suitable opening (not shown), heat the vaporizer, and pass out through the opening 62. It will be seen that exhaust gases pass around the chambers in 105 which the air and fuel are baffled and mixed, and it will also be seen that the air which is admitted through the tube 27 is heated as it passes up through the vaporizer. It is advantageous to afford this secondary air supply 110 in the manner shown; that is, with the air entering from the opposite side of the vaporizer than the primary air supply; but it is within the invention to supply the secondary air by other means, as for instance, by a tube 115 extending out through the plate 31.

When the oil is mixed at the chamber 53, it passes to the chamber 63 where it is vaporized. The manner in which the oil passes from one chamber to the other is important, in that the heavier particles of oil are brought into close proximity to the walls of the exhaust gas chambers. This is accomplished by directing the mixture in a swirling manner through a passageway wherein there is a series of openings arranged so that lighter particles are designed to go through some openings, and heavier particles through other openings. For this purpose a plurality of rings 64, progressively increasing in size are 120 125 130

secured together at spaced points, as by welding, as shown at 65 (Fig. 4) are provided. The mixture passing down and into the mixing chamber 53 takes a swirling movement 5 around the tube, and the oil and air mixture enters toward the chamber 63 in a swirling manner, as indicated by the arrows on the drawing. This results in the lighter particles clinging to the center, and the heavier particles 10 being thrown outwardly. Thus, the lighter particles enter a central passageway 66. The heavier particles enter through the openings 67 between any two of the rings, with the heaviest particles entering as at 67a. 15 Thus, the heavier particles are brought into close proximity to the hot walls which confine the exhaust gases. All of these oil particles are brought together in the hot chamber 63 where they are vaporized. 20 From here the oil vapor enters a chamber 70 and then passes through the outlet 71, controlled by a valve 72, to an engine. The chamber 70 is formed by a valve arrangement rotatably mounted in the vaporizer body and 25 having a wall 73. The vaporizer is provided with an inlet 74 adapted to be connected to a supply of high grade gasoline. This is for the purpose of starting the engine, and in 30 doing so, the valve is turned so that the wall 73 closes the vaporizing chamber 63, thus opening the inlet 74. This supplies the engine with a high grade fuel, such as gasoline, which easily starts the engine. When the 35 engine and the vaporizer become sufficiently heated, the valve is turned back to the position shown in Fig. 1, thus shutting off the supply of high grade gasoline and opening up the low grade oil vapor. As shown in Fig. 3, the valve in the vaporizer is provided with 40 an arm 75, which is connected by means of a link 76, to the arm 4 of the plug valve 3. Thus the two valves work in unison, which is thought to be a preferable manner of operation. The vaporizer is provided with a 45 cap 77 which can be removed so that the interior of the vaporizer can be cleaned out from time to time.

Instead of using a high grade fuel for 50 starting the engine in order to first heat up the vaporizer, the vaporizer may be first heated by the use of a pilot light or by the use of an electrical heating element. An important 55 feature is the heating of the incoming oil as it passes through the body of the vaporizer through the pipe 10. It is important, however, not to heat the oil enough so that it vaporizes while in the pipe 10 but to heat the oil to a point just below its vaporizing point. I have found that the mixing of cold air with 60 this heated oil, which comes from the nozzle 25, the air coming through the ports 30, causes an efficient breaking up of the oil and that the results are better than if the oil coming through the nozzle 25 is partly vaporized. 65 The volume of air coming through the tube

27 acts as an insulating or cooling agent for the oil in the pipe 10. By adjusting the air inlet ports 18 and 19 as above described the volume of air in the tube 27 can be regulated to nicely determine the degree at which 70 the oil is heated.

The vaporizer can be used with engines of low compression or high compression type. With the high compression motors there is a 75 tendency for the setting up of a knocking, especially with the use of heavy oils. When the vaporizer is to be used with high compression motors it is desirable to mix with the vaporized oil vapor a part of the exhaust gases. The oil which is vaporized in the 80 chamber 63 is what is known as a dry mixture; or in other words, a thoroughly vaporized oil. For this purpose of mixing with this dry mixture some of the exhaust gases the vaporizer may be provided with a small 85 opening 63a which permits the passage of some of the exhaust gases into the oil vapor which is passing to the engine. This adds to the dry mixture a quantity of exhaust gases including water vapor and carbon dioxide, 90 which is effective in eliminating knocks characteristic of high compression engines.

Claims:

1. A fuel oil vaporizer comprising a body having a mixing chamber for fuel oil and air, a plurality of baffles in said mixing chamber, and a vaporizing chamber for the mixture, said chambers being connected by a passageway, said passageway including a plurality of openings progressively arranged from the central portion of the passageway to a point near the walls of the passageway. 95

2. A fuel oil vaporizer comprising a body having a mixing chamber of uneven internal contour for fuel oil and air, a plurality of baffles in the said mixing chamber having a contour complementary to a portion of the internal contour of the mixing chamber and arranged to cooperate therewith to form a tortuous passageway, and a vaporizing chamber for the mixture, said chambers being connected by a passageway, said passageway including a plurality of openings progressively arranged from the central portion of the passageway to a point near the walls of the passageway. 105 110

In testimony whereof I affix my signature.

CARL W. SCHUDDIG.
